UNITED STATES PATENT OFFICE.

FRANK G. CHARLES, OF GALESBURG, ILLINOIS.

IMPROVEMENT IN WINDMILLS.

Specification forming part of Letters Patent No. **131,426**, dated September 17, 1872.

To all whom it may concern:

Be it known that I, FRANK G. CHARLES, of Galesburg, in the county of Knox and State of Illinois, have invented a new and useful Improvement in Wind-Wheels; and I do declare that the following is a true and accurate description thereof, reference being had to the accompanying drawing and to the letters of reference marked thereon and being a part of this specification, in which—

Figure 1 is a vertical longitudinal section of the wheel and attachments. Fig. 2 is a plan of the operative parts. Fig. 3 is an elevation of the swivel and spider.

Like letters refer to like parts in each figure. The nature of this invention relates to an improvement in that class of wind-wheels which is employed for pumping water; and has for its object to provide an automatic device for throwing the sails out of wind when the tank is filled, and to so pivot the said sails to their hub that, in combination with the governing device and a float, they will ease up out of the wind when blowing hard. The invention consists in the peculiar construction and arrangement of the several parts for the several purposes, as more fully hereinafter set forth.

In the drawing, A represents the wheel-shaft, journaled in bearings in a bracket, B, revolving in a tubular vertical support, C. D is the vane secured to the opposite side of the bracket. E is the hub secured to the outer end of the shaft A. In the periphery of this hub are pivoted the arms F of the sails G, which are secured to their arms so as to have a little more area on the side of the arm toward the vane, so that the tendency of the wind would be to bring the sails edgewise to it. H is a connecting-rod, pivoted to a crank at the rear end of the shaft A and to the piston-rod of a pump below, (not shown.) I is a spider, sleeved on the shaft behind the wheel, with an arm for each sail, to which it is connected at the front side by a link, a, pivoted at the other end to an arm, b, projecting from the front side of the sail, near its base and behind its axis. On the back of the spider is a swivel, I', with

which engages a yoke, c, to which is pivoted a forked rod, d, sliding in bearings on top of the bracket. J is a vertical standard on the vane-arm, to which is pivoted a lever, K, weighted as at L. This lever K is forged with two arms, the vertical one, e, rising from the fulcrum, and a horizontal one, f, on a prolongation toward the wheel. The top of the arm e is connected, by a rod, g, to the forked rod, d, which is in turn connected to the spider. M is a float whose weight is graduated to the size of the wheel, and is suspended in the tank by a rod, h, from the end of the arm f of the lever K, said rod passing up through the tubular support C. When the float M is buoyed up by the water rising in the tank the weight L, drawing back the spider through its connections, rotates the sails G so as to bring them edgewise to the wind, when the wheel will cease to revolve. When the water is drawn down away from the float the latter overbalances the weight L, so as to bring the faces of the sails athwart the wind, at an angle with its course.

During the prevalence of a gale, by reason of the eccentric pivoting of the sails, the latter are more or less rotated on their axes, bringing them in the plane of the course of the wind, consequently reducing the speed of the wheel and necessarily lifting the float M from the water. If the float be heavily weighted the higher will be the speed of the wheel, as more power must necessarily be exerted upon the sails to lift it.

What I claim as my invention, and desire to secure by Letters Patent, is—

The construction and arrangement, with relation to the shaft A, bracket B, tubular support C, vane D, hub E, arms F, and sails G, of the spider and swivel I I', arms b, links a, yoke c, connecting-rod d, g, weighted bell-crank lever K, standard J, rod h, and float M, substantially as and for the purpose set forth.

FRANK G. CHARLES.
